L. M. ELLIS

HEATING SYSTEM

Filed July 8, 1922

UNITED STATES PATENT OFFICE.

LEWIS M. ELLIS, OF CONNERSVILLE, INDIANA, ASSIGNOR TO WINSLOW SAFETY HIGH PRESSURE BOILER COMPANY, OF CHICAGO, ILLINOIS, A CORPORATION OF ILLINOIS.

HEATING SYSTEM.

Application filed July 8, 1922. Serial No. 573,603.

To all whom it may concern:

Be it known that I, LEWIS M. ELLIS, a citizen of the United States, residing at Connersville, in the county of Fayette and 5 State of Indiana, have invented a certain new and useful Improvement in Heating Systems, of which the following is a full, clear, concise, and exact description, reference being had to the accompanying 10 drawings forming a part of this specification.

The present invention relates to heating systems, and pertains generally to that 15 class of heating apparatus having application to ovens, kilns, vats and the like, designed for drying and processing.

One of the principal objects of the invention is to provide a heating system employing steam at low or nominal pressures, but 20 superheated to a comparatively high temperature and circulated in a comparatively large volume.

Another object of my invention is to provide an improved method of and means 25 for heating which will be capable of employing air and steam in alternate order or in conjunction with each other. According to one conception of my invention, I propose using air exclusively in the initial 30 warming up of the system. This pre-heats the conduits, the radiating surfaces, impeller and all other surfaces with which the heating medium contacts so that when the steam is finally introduced into the system, 35 the entire system will be at such a temperature that there will be a minimum tendency for condensation.

According to the preferred embodiment, 40 the steam is circulated through a system characterized by the use of large sheet metal pipes and conduits and by the use of hollow metal walls, floors and ceilings surrounding the kilns or ovens. The system may be thus likened to a "furnace pipe" 45 system employing a large volume of steam circulated at a comparatively low pressure. The steam is preferably introduced into the system from an outside source and may be comparatively wet or saturated, this wet 50 steam being first superheated in the super-heating unit before being circulated through the closed system. The initial pre-heating of the system by the circulation of heated air therethrough minimizes the 55 losses from condensation, but such losses as

do occur after the circulation of the super-heated body of steam has been built up may be replenished by the admission of more steam from the outside source.

The accompanying drawing is a dia- 60 grammatic representation of a preferred embodiment of my improved heating system.

The body of air or steam is circulated 65 through the system under the impelling action of a suitable centrifugal blower 1. The tangential outlet 2 of the blower discharges into the manifold conduit 3 which flares out to make connection with the plurality of transverse heating tubes 4 in the 70 heater 5. This heater may be of any preferred type and construction, being preferably of a type, however, having direct convection of heat from the combustion chamber to the heating tubes. In the conventional form of heater shown, the tubes 4 extend between insulated side walls 6 across one or more heating flues extending longitudinally of the setting. A combustion chamber 7 is provided in the lower 75 part of the setting, and a perforated fire arch 8 is preferably extended across the combustion chamber. As above mentioned, the products of combustion from the chamber 7 are preferably brought into contact with the air tubes 4 by circulating the products of combustion around the tubes through one or more passes above the arch 8.

The air from the blower 1 may be given 80 a single pass through the tubes 4, or, if desired, the tubes can be connected in series so as to compel the air to go through a series of passes transversely of the heater. The heated air is discharged into a manifold 11 85 which covers the ends of the tubes discharging from the side wall of the heater, this manifold communicating with a conduit or a system of conduits 12 extending to the various ovens, kilns or the like to be heated. An oven or kiln is diagrammatically illus- 90 trated at 14, being illustrative of any enclosure adapted to be heated. This enclosure is surrounded on one or more sides by outer walls 15 which define heating chambers or 95 jackets 16. These heating chambers 16 are representative of hollow walls, partitions, floors and ceilings, such as are now used on a large scale in systems employing heated air under comparatively low pressure. 100 105 110

The heating chambers of the oven or series of ovens are connected to a common return conduit 18 which extends back to the central intake 19 of the blower 1. The volume of steam which is introduced in the system after the preliminary warming up by the circulation of heated air is preferably introduced into this return conduit 18. This insures that the live steam entering the system will be forced to circulate through the heater 5 before contacting with any of the heating walls of the ovens or the connecting conduit system. The steam is introduced through any suitable pipe 21, preferably in the form of a nozzle having its outlet directed in the course of flow to add the impulse of the steam to the circulation. This steam nozzle is supplied from any suitable boiler 22 under the control of a valve 23, the steam delivered therefrom being of any desired pressure and temperature. Generally this steam will be drawn from any convenient source of supply and will hence be wet or saturated. The blower 1 is driven in any suitable manner, as through the belt 24 engaging over the pulley 25. The speed of the blower 1 may be made regulatable so as to control the velocity of the circulation and thereby the quantity of heat conveyed to the oven or enclosure 14. A suitable flap valve 26 is pivoted at 27 to cover a discharge outlet in the return conduit 18, through which discharge outlet the air can be expelled when changing from air to steam.

When the system is put into operation, combustion is initiated in the heater 5 and the blower 1 is put into motion for impelling a circulation of air through the tubes 4 and through the system for the preliminary warming of the system. After the system has been brought up to the desired temperature, as for minimizing condensation, the valve 23 is opened and steam is gradually introduced into the system through the nozzle 21. The flap valve 26 in the return conduit 18 is opened and the heated air is discharged through the valve opening as it is displaced by the volume of steam entering through the nozzle 21. Steam is admitted into the system until the most efficient pressure is obtained consistent with the character of the system. The present system is characterized by the use of sheet metal conduits of large volume, and large volume heating chambers in the walls, floors and ceilings of the oven or kiln, and consequently the pressure of the steam must be maintained comparatively low to prevent leakage or rupturing of these conduits or heating chambers. By virtue of the above characteristics the present system is capable of effectively utilizing air as the heating medium, so that for emergency use, and possibly for certain classes of heating, air may

be utilized in lieu of steam. The use of steam in the present system has inherent thermal advantages, however, over the use of air, particularly in the higher specific heat of the steam, which is much in excess of that of air, and the higher heat conductivity of the steam. Any steam losses from the system are replenished by the introduction of further steam through the nozzle 21. When cooling off or stopping the operation of the system, it may be desirable to shut off the steam a few minutes in advance and admit air in its place so as to prevent the accumulation of moisture in the conduits and heating chambers when the temperature drops below that of the steam, which moisture might be precipitated from the condensation of steam if the operation were interrupted with steam in the conduits.

The type of heater illustrated at 5 admirably serves the two-fold function of heating the relatively large volume of air circulated through the system, and also of superheating the relatively large volume of steam when that is circulated through the system. The steam at nominal or low pressures is superheated in this heater to a temperature above saturation for circulation through the system. The rate of heat transfer can be regulated through a considerable range by controlling the rate of firing at the heater 5 and the speed of the blower 1.

I claim:

1. In a steam heating system, a blower for circulating a volume of air through the system, said blower including an inlet and outlet, a heater having a plurality of heating passages through which the air circulated by the blower is adapted to be passed, a conduit connecting the outlet of the said blower to the plurality of passages in the said heater, a heating chamber, a conduit for conducting the air to the said heating chamber, a return conduit for conducting the air from said heating chamber to the inlet of said blower, a nozzle for introducing steam into the system after the same has been preheated by the heated air, and a valve in the said return conduit for venting the air from said system after the latter has been preheated.

2. The method of heating in a system of the class described, which consists in circulating a volume of air through the system, heating the air for preheating the system, circulating a volume of steam through the system after it has been preheated by the volume of air, and venting the air displaced from the system by the steam.

3. The method of heating in a system of the class described, which consists in circulating a volume of air through the system, heating the air for preheating the system and for causing the air to absorb moisture therein, circulating a volume of steam

through the system after it has been pre-heated by the volume of air to displace the air from the system, and venting the air displaced from the system by the steam.

5 4. The method of heating in a system of the class described which consists of circulating a volume of steam through the system, circulating a volume of air through the system to absorb moisture therein, and displacing the air by a second volume of steam.

10 5. The method of heating in a system of the class described which consists of circulating a volume of steam through the system, circulating a volume of air through the system, heating the air to cause it to pre-heat the system and to absorb condensate therein, displacing the volume of air by a second volume of steam, and venting the displaced air from the said system.

15 6. In a steam heating system, means for circulating a volume of air through the system, means for heating the circulated

air, a heating-chamber adapted to be pre-heated by the circulated air, means for introducing steam into the system after the 25 system has been preheated by the circulated air, and means for discharging the air from the system after the system has been pre-heated.

7. In a steam heating system, means for 30 circulating a volume of air through the system, means for heating the air for pre-heating the system and for causing the air to absorb moisture therein, means for circulating a volume of steam through the 35 system after it has been preheated by the air, said volume of steam displacing the volume of air therein, and means for allowing the air displaced to escape from the system. 40

In witness whereof, I hereunto subscribe my name this 28th day of June, 1922.

LEWIS M. ELLIS.
